[57] CLAIM

The ornamental design for a popcorn receptacle for use primarily in a microwave oven, as shown and described.

DESCRIPTION

FIG. 1 is a side elevational view of a popcorn receptacle for use primarily in a microwave oven showing my new design;

FIG. 2 is a top plan view;

FIG. 3 is a bottom plan view;

FIG. 4 is an enlarged sectional view taken along line 4—4 of FIG. 2; and

FIG. 5 is an enlarged sectional view taken along line 5—5 of FIG. 2;

FIG. 6 is an enlarged sectional view taken along line 6—6 of FIG. 2.

FIG. 1

FIG. 2

FIG. 6

FIG. 4

FIG. 3

FIG. 5
